CLAIM

The ornamental design for a metal shaping apparatus, as shown.

DESCRIPTION

FIG. 1 is a perspective view of a metal shaping apparatus according to an embodiment of the invention.

FIG. 2 is a side planar view of a metal shaping apparatus according to an embodiment of the invention.

FIG. 3 is a top planar view of a metal shaping apparatus according to an embodiment of the invention.

FIG. 4 is a front planar view of a metal shaping apparatus according to an embodiment of the invention.

FIG. 5 is a rear planar view of a metal shaping apparatus according to an embodiment of the invention; and,

FIG. 6 is a perspective view of a metal shaping apparatus according to an embodiment of the invention with a portable stand in phantom.
